Primary Examiner — Adir Aronovich(74) *Attorney, Agent, or Firm* — Cox Smith Matthews Incorporated(57) **CLAIM**

The ornamental design for a gel holder, as shown and described.

DESCRIPTION

FIG. 1 is a front perspective view showing my new design for a gel holder;

FIG. 2 is a front elevational view thereof;

FIG. 3 is a top plan view thereof;

FIG. 4 is a left side elevational view thereof;

FIG. 5 is a rear elevational view thereof;

FIG. 6 is a bottom plan view thereof;

FIG. 7 is a right side elevational view thereof; and,

FIG. 8 is the gel holder in a folded position and attached to an electronic flash unit. The broken line portions are shown to illustrate environment only and form no part of the claimed design.
